UNITED STATES PATENT OFFICE.

PEMBROKE D. HARTON, OF PHILADELPHIA, PENNSYLVANIA.

CAKE-COATING MACHINE.

1,036,107.

Specification of Letters Patent. Patented Aug. 20, 1912.

Application filed August 17, 1903. Serial No. 446,840.

To all whom it may concern:

Be it known that I, PEMBROKE D. HARTON, a citizen of the United States, residing in Philadelphia, Pennsylvania, have invented 5 certain Improvements in Cake-Coating Machines, of which the following is a specification.

My invention relates to cake coating machines; and the object of my invention is to 10 provide a machine for depositing soft dough, macaroon, melted fondant, chocolate, marshmallow paste, or other material of a similar or like nature, upon the surface of baked cakes which are fed by suitable means to a 15 common depositing point.

My invention is fully shown in the accompanying drawings, in which:

Figure 1, is a side elevation of the complete machine forming the subject of my invention; Fig. 2, is a plan view of the same; Fig. 3, is a sectional elevation looking in the direction of the arrow *x*, and taken on the line *a*—*a*, Fig. 2; Fig. 4, is an enlarged sectional view of a part of the structure, showing the application of the coating material to the cakes, and Fig. 5, is a sectional view, taken on the line *b*—*b*, Fig. 1.

My present machine embodies certain improvements in the structure of my prior Patent No. 647,403, dated April 10, 1900, and includes certain details of my several pending applications relating to the coating of cakes. In my earlier patent above referred to, means are provided for holding 30 the cakes at a common point whereby icing may be deposited thereon, such means consisting of a suction or vacuum box having an open top over which a belt travels. Such belt is apertured and cakes disposed over 35 said apertures are fed by the belt to said suction box and there held while the icing is deposited and released; the purpose of holding the cakes by suction being to break the connection between the icing on the cake 40 and that flowing from the delivery spouts. Similar means, operating, however, in a slightly different way, will be employed in my present structure. The essential feature 45 of my present invention, however, is the particular form of the feeding device.

In the drawings herewith, 1 represents

a hopper, into which coating material is placed, which hopper is divided by a movable partition plate 2 which plate may extend into the discharge passage for the material whereby I may provide means for effecting the deposit of two kinds of material upon the cakes. The hopper is carried by a suitable supporting arm 3 extending from a bracket 4, which arm is longitudinally apertured at 5 for the passage of a feeding structure which is combined with the partition plate. This feeding structure comprises feeding passages 6 on the opposite side of said partition plate for two kinds of material. The lower end of this feeding structure has its outer walls grooved at 7, and disposed in registry therewith is a member 8 forming part of the material delivery spout. This member is secured to the feeding structure by means of plates 9 secured by screws 10.

The feed spout proper comprises a portion 11 arranged to telescope the portion 8, and springs 12 are provided to return it to the lowered position after it has engaged the cake. In the present instance this structure comprises angle pieces 13 and 14, one of which carries a member 15 which forms the side wall and bottom of one side of the delivery spout, and the other carries a member 16 which forms the side wall of the other portion of the delivery spout. The first member is provided with a series of holes 17, from each of which depend nozzles 18, while the other member has a plate 19 secured thereto with a series of nozzles 20 surrounding the nozzles 18 whereby the material of differing color or character to be deposited on the cakes may be extruded from both nozzles. The cakes are brought to a position directly beneath these nozzles by means of a suitable carrying chain and positioning means illustrated in my application for patent, filed May 8, 1903, Serial No. 481,586.

Carried by the bed plate of the machine is a casing 22 forming a suction or vacuum box, communicating by means of a pipe 23 with a suitable air exhausting apparatus. The box is apertured at 24 and 25, top and bottom, and arranged to cover the bottom

apertures is a plate 26 forming a valve, which plate is operated by an arm 27 pivoted at 28 and actuated by a cam 29, as shown in Fig. 4.

5 When the cakes are brought to the position shown in Fig. 3, the mechanism is automatically operated to shift the valve plate 26 to the open position, and under the suction created therein such cakes will be held 10 in place. The nozzles for delivering the material to be deposited are then lowered into contact with the cakes, and compression of such material within the feeding structure due to the telescoping of one part with 15 respect to the other as described, will cause such material to flow onto said cakes, and during such action the feeding means are replenished with such material to be deposited. This is accomplished in the following manner: The hopper for the coating material has its bottom opening normally closed by plates or ribs 30 disposed on both sides of the central partition plate 2 and lying at a point just below the bottom 25 wall 31 of said hopper. Arranged to move opposite the feeding device in the wall of the same, are pistons 32 connected at 33 to links 34, which links are in turn connected to bell-crank-levers 35 pivoted at 36 and 30 operated by means of rods 37 from cams 38 driven by the main driving shaft of the machine. Upon lowering the feeding device, the central partition plate carries the material down, and the ribs 30 of the same 35 close off the connection of the material in the upper part of the structure with that in the feeding channel.

Mounted at the sides of the bed plate are 40 projections 39, and when the telescoping portion of the feeding structure strikes said projections, the delivery spout is caused to telescope and eject the coating material accumulated within the same from the several nozzles.

45 When the central partition plate is in the fully lowered position, the pistons are moved out and draw into the spaces 40 a supply of coating material, which supply is just sufficient in amount to take the place of that 50 ejected onto the cakes, and when said partition plate is raised, the pistons travel in and force the coating material into that portion of the feeding channel below the ribs 30.

The lowering of the hopper is timed to 55 occur when cakes are in place over the suction box, and suitable mechanism is employed to effect this action.

If desired, I may omit one nozzle and feed the material from the other from one 60 side only of the hopper. Material of the same character may be fed onto the cakes from both nozzles, or such material may be of two kinds or two colors, as desired.

When the cakes are finished, they are

pushed by the succeeding row to be coated 65 onto a suitable carrier, from which they are deposited upon boards in the same manner as in the structure referred to in my prior patents.

I claim:

1. In a cake coating machine, the combination of means for feeding cakes to a common point, means for maintaining said cakes in such position, a hopper having compartments for coating material, a vertically movable structure forming a bottom for said hopper and having a plurality of chambers communicating with said compartments, outlet nozzles communicating with said chambers for the simultaneous deposition upon each cake of coating material from each chamber, horizontally disposed pistons for moving said coating material to the chambers of the bottom structure, and means for moving said bottom independently of the hopper to bring said nozzles into proximity with the cakes. 70 80 85

2. In a cake coating machine, the combination of means for feeding cakes, an icing hopper, delivery spouts communicating with 90 said hopper, a partition plate for said hopper whereby the latter may contain material of different kinds for delivery to concentrically arranged delivery spouts, said partition plate carrying the bottom of the hopper which is normally closed, and means for moving said plate whereby the bottom may be opened for the delivery of the material. 95

3. In a cake coating machine, the combination of a hopper for coating material, a 100 movable partition plate in said hopper, ribs carried by said plate and forming a movable bottom for the hopper, lateral passages arranged below said hopper, feed passages disposed below said lateral passages, said 105 lateral passages being in communication with the hopper when the partition plate is in one position and in communication with the feed passages when the partition plate is in another position, and means for causing a flow of material into said lateral passages, the ribs of said partition plate forming a valve and holding the coating material against upward movement when extruded from the nozzles. 110 115

4. In a cake coating machine, the combination of a hopper for coating material, a 120 movable partition plate in said hopper, ribs carried by said plate and forming a movable bottom for the hopper, lateral passages arranged below said hopper, feed passages disposed below said lateral passages, said 125 lateral passages being in communication with the hopper when the partition plate is in the lowered position and in communication with the feed passages when the partition plate is in the upper position, pistons for causing a flow of material into said lat-

eral passages, a delivery nozzle in communication with said hopper, and means for telescoping said nozzle to deliver the coating material, the ribs of said partition plate 5 forming a valve and holding the material against upward movement when extruded from the nozzles.

In testimony whereof, I have signed my name to this specification, in the presence of two subscribing witnesses.

PEMBROKE D. HARTON.
